Primary Examiner — Sharon S Oum(74) *Attorney, Agent, or Firm* — McGarry Bair PC(57) **CLAIM**

The ornamental design for a ceiling fan motor housing as shown and described.

DESCRIPTION

FIG. 1 is a top perspective view of a ceiling fan motor housing, shown in the environment of a ceiling fan, showing my new design;

FIG. 2 is a top view thereof, having the ceiling fan environment removed;

FIG. 3 is a bottom view thereof; and,

FIG. 4 is a front view thereof, with the rear, right, and left side views being identical thereto.

Portions of the ceiling fan motor housing and ceiling fan environment are shown in broken lines. Portions shown in broken lines form no part of the claimed design.
